United States Patent Office

Des. 186,482
Patented Oct. 27, 1959

186,482

WARNING SIGN

Joseph G. Schwartz and William Cheifetz,
Montreal, Quebec, Canada

Application November 14, 1958, Serial No. 53,380

Term of patent 14 years

(Cl. D72—1)

Fig. 1

Fig. 2

Fig. 3

Fig. 1 is a front elevational view of a warning sign embodying our new design;

Fig. 2 is a side elevational view; and

Fig. 3 is a top plan view.

The rear of the warning sign is substantially plain with the exception of the three light elements which have the same appearance both front and rear.

We claim:

The ornamental design of a warning sign, as shown and described.
